(57) **CLAIM**

The ornamental design for a bench, as shown and described.

DESCRIPTION

FIG. 1 is an isometric view of a bench showing a first embodiment of my new design.

FIG. 2 is a left side elevational view of the bench of FIG. 1, the right side elevational view being a mirror image thereof.

FIG. 3 is a front elevational view of the bench of FIG. 1.

FIG. 4 is a bottom plan view of the bench of FIG. 1.

FIG. 5 is a top plan view of the bench of FIG. 1.

FIG. 6 is a back elevational view of the bench of FIG. 1.

FIG. 7 is an isometric view of a bench showing a second embodiment of my new design.

FIG. 8 is a left side elevational view of the bench of FIG. 7, the right side elevational view being a mirror image thereof.

FIG. 9 is a front elevational view of the bench of FIG. 7.

FIG. 10 is a bottom plan view of the bench of FIG. 7.

FIG. 11 is a top plan view of the bench of FIG. 7; and,

FIG. 12 is a back elevational view of the bench of FIG. 7.

The slats of the bench are shown broken-away in FIGS. 1, 3-6, 7, and 9-12, to indicate that a specific length forms no part of the claimed design.
